(57) **CLAIM**

The ornamental design for an automotive seat, as shown and described.

DESCRIPTION

FIG. 1 is a front/left side perspective view of an automotive seat in accordance with the present invention, wherein a front/right side perspective view is a mirror image thereof; FIG. 2 is a rear/left side perspective view of the automotive seat of FIG. 1, wherein a rear/right side perspective view is a mirror image thereof; and, FIG. 3 is a front perspective view of the automotive seat of FIG. 1.

The broken lines are for illustrative purposes only and form no part of the claimed design.
